[57] **CLAIM**

The ornamental design for a flow detector for an intravenous administration set, substantially as shown and described.

DESCRIPTION

FIG. 1 is a perspective view of a flow detector for an intravenous administration set, showing our new design;

FIG. 2 is an end view thereof;

FIG. 3 is an end view from the opposing end thereof;

FIG. 4 is a front elevational view thereof;

FIG. 5 is a back elevational view thereof;

FIG. 6 is a top plan view thereof; and

FIG. 7 is a bottom plan view thereof.

The broken line showing of a vented piercing pin and drip chamber with tubing in FIGS. 2, 3, 4, 5, 6 and 7 is for illustrative purposes only.
